BAGGAGE SHELF OR THE LIKE

Irene Berger, Flushing, N.Y.

Application April 21, 1958, Serial No. 50,555

Term of patent 7 years

(Cl. D33—3)

The back of the baggage shelf is plain and unornamented.

The dominant features of my design reside in those portions shown in full lines on the drawing.

I claim:

The ornamental design for baggage shelf or the like, as shown and described.
